UNITED STATES PATENT OFFICE.

JOSEPH D. TESSIER, OF WORCESTER, MASSACHUSETTS.

COMBINATION LETTER-SHEET AND ENVELOP.

1,220,474.

Specification of Letters Patent. Patented Mar. 27, 1917.

Application filed October 12, 1911. Serial No. 654,218.

To all whom it may concern:

Be it known that I, JOSEPH D. TESSIER, a citizen of the United States, residing at Worcester, in the county of Worcester, and 5 in the State of Massachusetts, have invented certain new and useful Improvements in a Combination Letter-Sheet and Envelop; and I do hereby declare the following to be a full, clear, concise, and exact description of 10 the invention, such as will enable others skilled in the art to which it appertains to make and use the same, reference being made to the accompanying drawing, which forms a part of this specification.

15 My invention relates to improvements in that class of combination letter sheets and envelops in which the letter sheet coöperates with the envelop to form a unit article.

20 The object of my improvement is to provide a simple and cheap device for maintaining the letter sheet and the envelop in a folded unit.

A further object is to provide a foldable or locking means to hold the envelop and 25 the letter sheet in a folded position in such a manner as to prevent accidental or unauthorized opening thereof.

30 A further object is to furnish an article possessing certain advantages and details 35 of construction over those heretofore constructed as will be apparent from the following description and as specified in the claims.

In the drawing,

35 Fig. 1 is a plan view of the unfolded letter sheet and envelop,

Fig. 2 is a profile view of my device in a 40 stage of process of folding the same preparatory to locking the parts together,

Fig. 2' is a similar view to Fig. 2 showing a slightly modified form thereof,

Fig. 3 is a plan view showing the article completely folded,

Fig. 4 is a plan view of a modification,

Fig. 5 is a section along the line 1—1 of Fig. 1 and

Fig. 6 is a similar section of the modified form shown in Fig. 2'.

50 Similar letters refer to similar parts throughout the several views. Referring first to Fig. 1 of the drawing my invention is made up principally of a letter sheet generally designated by the reference character L, an envelop portion C and a tab X. The envelop has the usual three tongues or flaps A, B, and B' foldable respectively on the

lines a, b, and b' and the body or face section C, which is generally of rectangular configuration. The tongues or flaps are gummed on their inner faces along the edges 60 in the usual manner.

The letter sheet is substantially rectangular in form and is made up of the sections D, E, F, and Y produced by folding the sheet at the lines d, e, f, and y. The upper 65 extremity of the letter sheet is shown at the line d, the sheet being integral with the envelop sheet. To the inner side of the face section C of the envelop, is partially glued or pasted a narrow strip or tab X, its length 70 being substantially the same as the width of the letter sheet. Only a portion x' of the width of the strip X is glued or pasted in contact with the envelop section C while the remaining portion X'' remains free for an 75 interlocking engagement with the strip Y at the lower end of the letter sheet when the whole is folded as will be more clearly seen from the disclosure below.

At the lower end of the letter sheet is a 80 strip or tab Y, preferably an integral part of the letter sheet, and substantially of the same length as the tab X and of a width corresponding to the width of the unglued portion x'' of the tab X. The tab Y has 85 been shown slightly tapered at the ends at t and t' for the purpose of facilitating its entering behind the free portion x'' of the tab X when folding the device.

In Fig. 2 is shown the letter sheet and envelop in the process of folding, the letter sheet being folded on the line d then folded back on the line e and then folded up on the line f and finally the interlocking tab Y folded in on line y and the tab slipped in 95 under the free portion x'' of the tab X. The flaps of the envelop sheet are then folded in and fixed in the usual manner.

Fig. 2' is a slight modification from the structure described above in connection with Figs. 1 and 2. In this form I have made the letter sheet separate from the envelop sheet and also longer in that its upper extremity terminates in the free strip x'' at line a, that is, I have made the letter sheet L, the strip X and a portion C' integral. This is more easily seen from a glance at Fig. 6. Beneath this letter sheet at such a place as is indicated at x' I have attached a narrow area of glue or paste whereby I may attach said letter sheet to the envelop 10 preparatory to folding it up and mailing 11

it. It is often desirable to have the letter sheet unencumbered from protruding ends or portions when writing upon it, and this is arrived at by fixing the same to the envelop sheet as aforesaid after the letter sheet is written upon. In other respects this device is the same as that represented in Figs. 1 and 2 and the folding process and the interlocking of the strips Y and x'' are performed in precisely the same manner.

Fig. 4 is another modification, wherein the letter sheet is made of a greater area than that shown in Fig. 1 by adding thereto rectangular wings W and W' foldable on the lines d'' , e'' , f'' , and d' , e' , f' , respectively. These wings may be made of lengths to suit the length of the letter sheet described in the foregoing part of this specification, areas R and R' inclosed by lines r' , r'' and u' and u'' being further added to conform to the full length of the letter sheet shown in Fig. 2. The rest of this form is in all respects the same as described above and the folding process and the interlocking of the strips Y and x'' are performed in exactly the same manner as described for the structure shown in Fig. 1.

When folded the letter is sealed and to all appearances it is no different from any other ordinary letter. If however one desires officiously to tamper with the device or for any other reasons attempts to see the contents one cannot do so without tearing it and thereby rendering oneself liable to detection, thus preventing one from seeing the contents unnoticeably. The above results and the advantages are all attained by virtue of a very simply, cheap and easily made interlocking device.

Having thus described my invention, what I claim as new and desire to secure by Letters Patent is;—

1. In a device of the character described, the combination of a letter sheet, a gummed area on the back of the letter sheet, an envelop sheet attached to the letter sheet by the gummed area, a free end on the letter sheet beyond the gummed area and a free end on the other side of the gummed area on the letter sheet.

2. In a combination letter sheet and envelop, an envelop sheet with flaps, a letter sheet, means for attaching the same together, means for foldably holding said letter sheet and envelop together as a unit, comprising a plurality of overlapping members and located between the envelop and letter when in folded position.

3. A combination letter sheet and envelop, a letter sheet, an envelop sheet, a plurality of overlapping members, one of said members being held adjacent to the envelop sheet, the other member being attached to the letter sheet, the first member occupying space provided between the second member and a portion of the letter sheet, the second member occupying space provided between the first member and the envelop, flaps on said envelop for retaining the letter sheet and the members in folded position when sealed, thus preventing an opening of the device without tearing at least one of said members and thus indicating an unauthorized opening of the article.

JOSEPH D. TESSIER.
